Rehemiah S Wood

UNITED STATES PATENT OFFICE.

NEHEMIAH S. WOOD, OF CHELSEA, MASSACHUSETTS.

ROTATING SELF-CLOSING CASE FOR PANTRY-SLIDES.

SPECIFICATION forming part of Letters Patent No. 416,146, dated November 26, 1889.

Application filed May 13, 1889. Serial No. 310,653. (No model.)

To all whom it may concern:

Be it known that I, NEHEMIAH S. WOOD, of Chelsea, in the county of Suffolk and State of Massachusetts, have invented certain new and useful Improvements in Rotating Self-Closing Cases for Pantry-Slides, of which the following, taken in connection with the accompanying drawings, is a specification.

The object of my invention is to so construct a casing and case for pantry and dining-room use that at no time will there be an open communication between the two rooms between which the device is placed, the case being made to revolve by the attendant and having two self-closing doors so arranged in connection with an automatic device that one of the doors shall be closed while the other is open. This object I attain by the mechanism shown in the accompanying drawings, in which—

Figure 1 is a vertical section showing the casing and case and their connected parts. Fig. 2 is a horizontal section taken on line $x-x$ of Fig. 1. Fig. 3 is a view in perspective showing parts of the revolving case, a part of one of the doors, and a part of the upper casing. Fig. 4 is a horizontal section taken on line $y-y$ of Fig. 1.

In the drawings, A represents a part of the fixed casing or wood-work in which my rotating case C is placed.

B is the base of the case, and it rotates on a pivot b. (See Fig. 1.) The base B has cords H H, working in grooves about it, as shown in Figs. 1 and 4. Each of the cords H H terminate in handles or knobs K³ K⁶, by means of which the attendant can, by drawing the cords, cause the case C to rotate.

The cords H H are arranged to draw about friction-pulleys L L, Fig. 4, so as to be easily moved and not to be worn by friction.

The case C has but one opening c c, Fig. 2, through which dishes and other articles may be placed in the case or taken from it.

D and D', Fig. 2, represent doors which are curved in horizontal sections, so as to be adapted to slide around on the curved track E and in the slot E', Figs. 1 and 2.

The doors D and D' are adapted to close the openings a a and a' a' in the casing, (see Fig. 2,) and are provided with stops and catches, so that they alternately close and

open their respective openings a a and a' a' in the stationary casing—that is, the opening (for instance, a a in Fig. 2) in the casing that is in conjunction with the opening c c in the rotating case C will not be closed, its door D being in the position shown in Fig. 2, but the door D' will be in position to close the opening a' a' in the fixed casing. 55

My device for causing the doors D and D' to move at times as desired I will now explain. On the outside of the rotating case C, Figs. 2 and 3, I have a catch-plate H⁵, having a notch H', (see Fig. 3,) which may catch 60 on to the post M, that extends from the interior of the doors. The catch-plate H is attached to a sliding rod H², which is held in place by the brackets H³ H⁴. At the top of the rod H² a lever K is pivoted by the pin h. 70 This lever K is pivoted at K', which acts as a fulcrum for it. The end of the lever K is bent, as shown at K², and is adapted to be acted upon by fixed cam-pieces, one of which is shown at L², Fig. 3. The cam-pieces L² are 75 attached to the upper part of the casing and are located near the door-post A⁴ A⁴.

The operation of my device is as follows: If we suppose the rotating case C to be in the position shown in Fig. 2, with the door D open, 80 and we wish to pass some article through from one room to another, the article is placed in the case C. Now the attendant pulls upon one of the cords H, (in this case the one attached to K⁴ or K⁶), so as to cause the case 85 to rotate in the direction of the arrow S, Figs. 2 and 4. This action will, acting through the stud M and catch-plate H⁵, cause the door D to slide around until it closes the opening a a, Fig. 2. At the time that the door D has 90 fully closed the opening a a the end K² of the lever K will have come in contact with the fixed cam L² (see Fig. 3) and will be depressed, thus lifting, through the rod H², the catch-plate H⁵ and freeing it from the stud 95 M on the door D. Now the door D stops and a continued movement of the rotating case C brings the other catch-plate in connection with the stud M', Fig. 2, on the door D', and a still further motion of the rotating case C 100 will cause the door D' to open and at the same time bring the opening c c of the rotating case C in junction with the opening a' a' of the fixed casing, so that the article in the

rotating case C may be taken out. By reversing these operations the position of the rotating casing C and the doors may be restored to their place, as shown in Fig. 2.

5 I claim—

In a rotating self-closing case for pantry-slides, the combination of the rotating case C, partially inclosed within an outer fixed casing and having an opening *c c* and catch-
10 plates H⁵ H⁵ on its outer surface, and base B,
having operating-cords H H, as described,
with the outer casing A, doors D, located in

said outer casing, each of said doors having a stud M upon it adapted to engage with the catch-plates H⁵ H⁵, substantially as and for 15 the purpose set forth.

In testimony whereof I have signed my name to this specification, in the presence of two subscribing witnesses, on this 10th day of May, A. D. 1889.

NEHEMIAH S. WOOD.
